TELEGRAPH TRANSMITTER

Howard L. Krum, Miami Beach, Fla., and Albert H. Reiber, Evanston, Ill., assignors to Teletype Corporation, Chicago, Ill., a corporation of Delaware

Application July 18, 1938, Serial No. 219,772

10 Claims. (Cl. 178—17)

The present invention relates to apparatus for the transmission of telegraph signals and more particularly to telegraph transmitters operated under the control of signal indicia on a strip.

5 The principal object of the present invention is the provision in a transmitter for transmitting signals in accordance with the indicia on a control strip, instrumentalities which permit accurate signal transmission at high speeds.

10 Another object of the invention is the provision of a transmitter of the aforementioned type which has its elements arranged to cooperate with a control strip with extreme accuracy and without mutilation thereof which, if occurred, might render its advancement irregular and interfere with signal transmission.

20 A feature of the invention resides in the separation of sensing and strip advancing instrumentalities of a transmitter capable of transmitting the signal for the last control indicia applied to the strip and their coordinate operation to avoid mutilation of the strip feeding perforations and thus insure its accurate and regular advancement.

25 Transmission of character identifying signals in telegraph systems is frequently achieved in accordance with a control strip including control indicia formed in varying combinations either by manually or remotely operated apparatus.

30 Specifically, the control indicia may be in the form of transverse rows of perforations formed in a tape either by a keyboard perforator or by a signal controlled perforator which is commonly referred to as a reperforator. The tape thus prepared passes through a transmitter or sensing mechanism to control correspondingly the transmission in succession of impulses identified with the perforations, which has its tape entrance channel separated from the tape exit channel of the perforator with the result that a short length 35 of tape extends between the perforator and transmitter and contains a group of perforations, for the last character perforated is not sensed unless instrumentalities are provided for advancing the tape to present such group of perforations to the transmitter. Prior to the transmission of signals for the succeeding groups of perforations, blank tape represented by the distance between the perforator and the transmitter is passed

40 through the transmitter and line time commensurate with said length of blank tape is consumed, with the consequent transmission of no intelligence.

45 The above and other objects of the invention are accomplished by the provision either of a

manually operated keyboard perforator or a signal controlled perforator operative in conjunction with a tape sensing mechanism including a plurality of sensing fingers set permutably in accordance with the perforations or control indicia 5 in the previously prepared control strip to control the transmission of impulses symbolic of the character to be reproduced. The perforator to which the invention has been specifically applied comprises a plurality of key levers arranged to 10 set permutably a plurality of bars which set correspondingly a plurality of interponents to control, upon the operation of a mechanically operated punch hammer, the operation of punches arranged in a transverse row to perforate a control strip in accordance with the code allocated to a depressed key lever. Cooperating with the code punches is a feed hole punch for inserting in the tape a feed hole which cooperates with a tape feeding mechanism of the sensing unit to 15 advance the tape therethrough step by step in order that the groups of perforations therein will be sensed successively.

20 The tape sensing mechanism includes two frames capable of oscillation about a fixed pivot 25 away from and toward the exit tape channel of the keyboard perforator. Normally, the tape entrance channel of the sensing unit is immediately adjacent the exit channel of the perforator and the tape passes directly from the perforator to 30 the sensing unit and without any exposed portion of the tape. When the perforator is operated, the tape feed mechanism thereof advances the tape and moves the sensing unit about its pivot a distance equal to the distance between the 35 transverse rows of perforations. The sensing fingers are mounted in one of the frames and sense the transverse row of perforations to control through appropriate levers the operative position of a contact operating member individual thereto for effecting, upon the operation of a cam distributor, the transmission of impulses corresponding to the setting of the sensing fingers. Mechanism for advancing the tape through the sensing unit or for effecting relative movement 40 between the sensing unit and the tape is mounted in the other frame. These frames are interconnected by springs and tend to follow each other.

45 The sensing unit operates at a definite predetermined speed, whereas the perforator may be operated at a speed dependent upon the speed of the operator. If the perforator is operated at a speed higher than the speed of rotation of the transmitting cam shaft, the tape will be fed at 50 55

a rate higher than the rate at which it is consumed by the sensing unit, in which case the two frames composing the sensing unit will be pushed in a counterclockwise direction about their pivot until they reach a predetermined position when, if the perforator is continued to be operated at a speed higher than the speed of operation of the transmitting cam shaft, the tape will be formed in a loop extending between the sensing unit and the perforator.

When a cessation in the operation of the perforator occurs, the tape will continue to be advanced through the sensing unit by the tape advancing mechanism thereof. When the loop of tape has been exhausted and the tape becomes taut between the sensing unit and the perforator, and provided operation of the perforator is not resumed, the sensing unit due to the cyclic operation of the tape advancing mechanism and its cooperation with the feed holes in the tape, will be moved in a clockwise direction toward the perforator and in such movement, which is step by step, the transverse rows of perforations will be sensed successively until the sensing head is brought in abutting relation to the perforator when mechanism is operated for discontinuing the operation of the tape advancing mechanism through arresting the rotation of the transmitting distributor cam drum.

Immediately that operation of the perforator is resumed, the tape will be advanced thereby and the one frame of the sensing unit will be moved about its pivots to start the distributor cam drum whereby the tape advancing mechanism of the sensing unit is operated and due to the fact that the tape between the perforator and sensing unit is taut, the sensing unit will be positioned to allow the sensing fingers to sense the row of perforations and transmit, through the operation of the transmitting cam drum, a corresponding signal. During transmission, the tape is gripped by a tape gripping element operated by a cam on the cam drum.

A better understanding of the invention may be had from the following description, taken in conjunction with the accompanying drawings, wherein

Fig. 1 is a front elevational view of apparatus embodying the invention;

Fig. 2 is another view of a part of the structure disclosed in Fig. 1 but showing the sensing unit displaced from the perforator;

Fig. 3 is a partial plan view of the essential elements of a keyboard perforator, tape sensing unit, and a signal transmitting device;

Fig. 4 is an end elevational view of the structure disclosed in Fig. 3;

Fig. 5 is a sectional view taken substantially along the line 5-5 of Fig. 3;

Fig. 6 is a detail view of the tape holding mechanism of the sensing unit; and

Fig. 7 is a circuit diagram of the electrical connections for the apparatus disclosed in Fig. 3.

The present invention may be considered as including three principal units, a tape perforator 9, a tape sensing unit 10, and a transmitting unit 11 (Fig. 3). Each of the several units is mounted on a base casting 12.

The perforator shown (Figs. 1 and 5) comprises a set of punches 13 movable through openings in upper and lower guide plates 14 and 15 and cooperating with a die plate 16, the plates 14 and 16 being spaced apart to form a tape guide. The punches 13 are selectively operated by an actuating member or hammer 17 and a set of

permutation bars or interponents 18 corresponding in number to the number of punches 13.

The hammer 17 is arranged to oscillate about a pivot 19 and is operated by arm 20 secured to one end of a lever 21 which is pivoted on rod 25 journaled in ears or projections 28 and 29 formed on the outer edge of a vertical wall 30 of a casting. Lever 21 carries at its opposite end a cam roller 32 which cooperates with a cam to operate cyclically hammer 17 and effect its oscillation and correspondingly the operation of the punch pins 13.

As disclosed in Fig. 1, a sleeve 33 having a pin 34 is adjustably mounted on arm 20. Pin 34 extends loosely through an aperture in hammer 17.

Mounted oppositely to arm 20 is a second arm 36 which, like arm 20, carries an adjustable sleeve 37 which has an elongated pin 38 in alignment with a punch pin 39. Punch pin 39 is partially enclosed in a housing 40 which conceals a spring 41 arranged to subject punch 39 to spring tension and restore it to its normal position. Punch 39 is guided at its upper and lower extremities by guide plates and cooperates with a die plate 42 which is separated from the upper guide plate to form a tape guide. Punch 39 serves to apply to tape 43 the feed holes in advance of the application of the code perforations by code punches 13. It is thus seen that for each operation of lever 21, the hammer 17 will be oscillated about its pivot 19 and the feed hole punch 39 will be moved upwardly by pin 38 which extends through an aperture in hammer 17 to perforate the feed hole, and will be restored to the position shown in Fig. 1 by spring 41 following the restoration of lever 21 to the position shown in Fig. 1.

The interponents or permutation elements 18 are movable back and forth over the face of hammer 17 and are adapted to be positioned in different combinations with their outer ends either in operative positions beneath the corresponding punches 13 or in inoperative positions out of alignment with punches 13.

The free end of hammer 17 is upturned, which portion is slotted to form guide channels for the forward end of each of the interponents 18.

Upon each setting of the interponents 18, lever 21 is oscillated and hammer 17 is moved about its pivot to form a row of perforations in tape 43 through the actuation of punches 13 corresponding to the setting of the interponents 18. Also, upon the operation of arm 21, pin 38 will be actuated and feed hole punch 39 will be operated to perforate the feed hole in tape 43 in advance of the formation of the row of code perforations.

Withdrawal of the feed hole punch is achieved by spring 41, whereas the withdrawal of the code punches is accomplished by a stripper bail 44 which is pivoted at 45 and which has secured thereto one end of a retractile spring 46. As disclosed, the punch pins 13 are each provided with a shoulder which cooperates with the lower surface of spring actuated stripper bail 44 so that when the punches 13 are raised, stripper bail 44 will be moved about its pivot 45 against the action of spring 46 and without any binding action on the punches 13. When hammer 17 is returning to the position shown in Fig. 1, spring 46 is effective to withdraw the actuated punches 13 and restore them to their normal unactuated position.

As previously described, for each operation of

lever 21, punch 38 is operated to form a feed hole adapted to be engaged by the pin teeth of a feed drum 47. The latter is provided with ratchet teeth 48 to be engaged by a feed pawl 49 which is pivotally mounted to hammer 17 and which is thus reciprocated upon each operation of the latter. A star wheel 50 and a knurled portion 51 which facilitates manual rotation are integrally formed and are secured to feed drum 47 by means 10 of a nut. Formed on the outside of a bearing sleeve through which drum 47 passes is a disc 52 provided with a projection 53 arranged to cooperate with an arm 54 formed on feed pawl 49 and arranged with an arm 55 cooperating with a slot 56 formed in a member 56 which is capable of being depressed to cause the withdrawal of feed pawl 49 from cooperation with teeth 48 and to back step the feed drum 47 to present a previously perforated row of perforations in alignment with the 20 code punches 13. A spring tensioned lever 57 pivoted on member 56 cooperates with star wheel 50 to back space the feed drum 47 and in turn the tape 43.

A spring 61 connected to the lower extremity of 25 feed pawl 49 serves to hold the feed pawl in engagement with ratchet teeth 48 of the feed drum and also normally holds the hammer 17 against the adjustable sleeve 33. When hammer 17 is moved in a clockwise direction by the action 30 of lever 21, spring 61 is extended. Consequently, when the force on lever 21 is relieved, the energy stored in spring 61 is released and hammer 17 is restored to the position shown in Fig. 1. Feed pawl 49 will also be restored and in being so moved, will rotate feed drum 47 to advance the 35 tape 43 to present a succeeding area thereof in alignment with the code punches 13. It is thus seen that for each operation of hammer 17, feed drum 47 will be rotated and the tape 43 will be 40 advanced step by step.

The interponents or permutation elements 18 are set in different combinations by a plurality of 45 key levers 62 suitably mounted on a pivot rod and normally upheld in raised position by individual springs, the levers being provided at their forward ends with key tops 63.

Beneath the key levers extend a number of 50 pairs of code bars, and since in the form shown there are five interponents 18, a corresponding 55 number of pairs of code bars are employed. Each pair comprises a bar 64 and 65 and each pair of bars is supported adjacent to each end by a rock arm 66. Each bar has its ends guided by oppositely disposed guide combs 58. These rock arms are pivotally mounted on a shaft 67 secured to a block 60 which extends transversely of the 60 bars 64 and 65 and which is arranged with a plurality of slots, one for each rock arm 66. A similar block 60 (not shown) is positioned adjacent the right-hand end of bars 64 and 65, as viewed in Fig. 1, which, too, carries a shaft 67 constituting a pivot for correspondingly shaped rock arms and which also serves to limit the endwise movement of bars 64 and 65. One pair of rock arms is 65 interposed between each two code bars comprising a pair, and the bars are held in proper spaced relation by the guide combs, one of which is shown at 58. The rock arms 66 are substantially T-shaped or widened at their upper ends and are 70 provided with offset lugs on opposite sides of and spaced some distance from the shaft 67. One of the lugs of each arm projects forwardly into a notch on the lower edge of the corresponding code bar 64 and its other lug projects rearwardly 75 beneath the lower edge of the corresponding code

bar 65. With this arrangement, the depression of either bar of a pair of code bars rocks the arms and lifts the other code bar.

Each pair of rock arms 66 is pivoted to a longitudinally movable permutation bar 68. In the 5 form disclosed, each bar 68 is connected to its individual lever 69, which is pivotally mounted on shaft 70 and which has its upper end connected to its interponent 18; that is, individual to each bar 68 and its companion interponent 18 is a 10 lever 69, so that for each movement of bar 68, corresponding movement of interponent 18 results.

Cooperating with the upper ends of levers 69, which are beveled, is a rod or roller 71 secured to 15 a U-shaped member 72 pivoted on rod 73 and urged into cooperation with the beveled end of each of the levers 69 by a spring 74. Rod 71 serves as a detent for levers 69.

Each of the key levers 62 which extends across 20 the code bars 64-65 is arranged, when operated, to engage and depress one of the code bars of each pair and thereby set the same and the permutation bars 68 and interponents 18 in a characteristic combination. Correspondingly, the 25 punches 13 will be operated in the same characteristic combination upon the operation of hammer 17 through lever 21.

For effecting the operation of the punches 13 through the interponents 18, each key lever 62 is 30 arranged to depress a universal bar 75 which is slidably mounted in the same manner as the code bars 64-65 and also cooperates with a pair of rock arms secured to a connecting link 76 to operate a bail 77 which constitutes a part of the 35 release mechanism effective for controlling the application of power to lever 21. As disclosed in Fig. 5, one arm of bail 77 engages an adjusting screw 78 fixed in one end of pivoted arm 79 to rotate, when the connecting link 76 is shifted, 40 arm 79 and remove the stop projection from the path of spring operated latch 80 and allow application of power to the cam for operating lever 21. The form of the release mechanism may correspond to that disclosed in Patent No. 2,019,505 to 45 A. H. Reiber of November 5, 1935, and consequently reference is made to such patent for a full and complete understanding of the construction and operation of the release mechanism which is operated by the universal bar upon the 50 depression of any of the key levers 62.

As disclosed in Fig. 3, an electric motor 88 has on its shaft a gear 89 which meshes with a gear 90 secured to a shaft 91 journaled in bearings 92 and 93. Also secured to shaft 91 is a gear 55 94 and the driving portion of a friction and positive clutch 95. Through the friction and positive clutch 95 a sleeve 96 on shaft 91 is rotated. Secured to sleeve 96 is a cam 97 which cooperates with roller 32 mounted on one arm of lever 21. 60

Upon the depression of any of the key levers 62, the code bars 64-65 will be operated as will the universal bar 75 to effect the operation of the clutch release mechanism. Upon the operation of such mechanism, clutch 95 is effective, whereupon power is communicated to sleeve 96 and thus to cam 97. As cam 97 rotates, lever 21 is operated to actuate hammer 17 against the action of spring 61. It is thus seen that, for each operation of a key lever, the code bars 64-65 will 70 be set in a characteristic combination, that the interponents 18 will be correspondingly set, that the clutch 95 will be effective and power will be applied to cam 97, and that through cam 97 the hammer 17 will be moved in a clockwise direc- 75

- tion, as viewed in Fig. 1, to cause code punches 13 to perforate the tape and punch 39 to perforate the feed hole, following which the hammer 17 is restored to its normal position by the action of spring 61, which serves also to advance the feed drum 47 through the operation of feed pawl 49 to advance tape 43 to present the succeeding area thereof in alignment with punches 13.
- 10 Between feed drum 47 and the entrance end of the tape guide formed between the plates 14 and 16 is a member 98 which has its upper surface curved to direct the tape from the feed wheel to the entrance of the tape guide in cooperation with a wire loop 99 formed to correspond with the contour of drum 47 and arranged to hold the tape firmly against the drum 47. The wire loop 99 is fastened to an arm 100 which is pivoted to permit the wire loop 99 to be moved free of the feed drum 47. Positioned above the code punches 13 is a chaff or chad chute 101.

The sensing unit

- 25 The sensing unit 10 includes two separate frames indicated generally by the numerals 105 and 106. Each of these frames is mounted on pivots such as 107 and is capable of being rotated on said pivots.
- 30 The carrier 105, as disclosed in Fig. 1, normally abuts the plates 14 and 16 of the perforator and has its entrance channel for the perforated tape in alignment with the exit end of the tape guide formed between plates 14 and 16 and formed by the separation of plates 108 and 109. Plates 108 and 109 are apertured to receive the reduced portion of a sensing pin such as 110. Inasmuch as there are five code punches 13, there will be a corresponding number of sensing fingers 110; that is, there will be a sensing finger 110 for each of the possible perforations appearing in a transverse row of perforations. The separation between the code punches 13 and the apertures in the plates 108 and 109 when the plates 108 and 109 abut the plates 14 and 45 16 corresponds to the normal spacing between successive transverse rows of perforations in tape 43. Usually the transverse rows of perforations are one-tenth of an inch apart and therefore the punches 13 and the apertures in plates 108 and 50 109 are correspondingly separated.

As disclosed in Fig. 4, the frame 105 includes, in addition to the plates 108 and 109, side members 111 and 112. These members are pivotally mounted on pivots 107.

- 55 Secured to side members 111 and 112 are L-shaped members 113 and 114, respectively. These members cooperate with portions of rod 115 which extends beyond the members 111 and 112 and to which one end of springs 116 and 117 are secured and which, as subsequently described, is fastened to side members 140 and 141. The opposite ends of springs 116 and 117 are secured to spring posts 118 and 119, respectively, which are secured to members 111 and 112, respectively.
- 60 The springs 116 and 117 serve to maintain the frame 105 normally under spring tension and tend to rotate the frame 105 in a clockwise direction, as viewed in Figs. 1 and 2.

Plate 109 is apertured to receive the end which 70 is serrated, as shown in Fig. 6, of a rod 125 which is operated cyclically and which serves to grip the tape 43 and hold it against movement during the period the fingers 110 are sensing the perforations in the tape 43.

- 75 Mounted on shaft 126 are a plurality of bell

crank levers 127, 128, 129, 130, 131, and 132. These bell crank levers are individual to a sensing finger 110, except bell crank lever 130, which is individual to rod 125. As disclosed, the sensing fingers 110 are pivotally secured to one arm of 5 their respective bell crank lever on a center line substantially coincident with pivots 107, which have an extension cooperating with a guide comb 133. Fastened to the other arm of the bell crank lever is a spring 134 which serves to rotate its 10 bell crank lever in a counterclockwise direction, as viewed in Fig. 2, and to move its sensing finger 110 vertically to sense the perforations in tape 43. If a perforation appears opposite a sensing finger 110, it moves to its fullest extent, whereas 15 if there is no perforation in alignment therewith, its movement is correspondingly restricted.

Common to all of the bell crank levers and cooperating with an arm thereof is a bail 137 pivoted at 138 and carrying on an extension a 20 cam roller 139. Bail 137 cooperates cyclically with the bell crank levers 127-132 to rotate the bell crank levers about their pivot 126 in a clockwise direction to withdraw sensing fingers 110 and tape finger 125 free of tape 43. The manner in which bail 137 is operated will be subsequently described.

The frame 106 includes side members 140 and 141, a cross piece 142, and a rotatable rod 143. Side members 140 and 141 are pivoted on pivots 30 107 about which frame 105 rotates.

Rod 143 carries a ratchet wheel 144 and a pin wheel 145 which cooperates with the feed hole perforations in tape 43 to advance the tape 35 through the sensing unit step by step. Step-by-step rotation of pin wheel 145 is accomplished through the cyclic operation of feed pawl 146 which cooperates with the teeth of ratchet wheel 144 to cause its step-by-step advancement. A detent 147 secured to side member 141 and to 40 which a spring 148 is secured, serves to hold the pin wheel in its advanced position.

As disclosed in Fig. 4, the lower end of stepping pawl 146 is secured to an arm of a lever 149 pivoted on stub shaft 150 and provided with a 45 cam roller 151. Pivoted on a rod 152 and tensioned against the pin wheel 145 is a tape finger 153 (Fig. 2).

The transmitting unit

50 Individual to each of the bell crank levers 127, 128, 129, 131, and 132 is a bell crank lever 154 pivoted on shaft 155 and held in proper position by spacing washers on shaft 155 and by a guide comb 156 which also has an extension cooperating with the lower arms of bell crank levers 127, 128, 129, 131, and 132 to effect their proper position.

Each bell crank lever 154 has a hook 157 at its upper end which engages the insulated upper 60 end of a spring contact 158 and each of the latter cooperates with a contact finger 159, the pairs of contact fingers being mounted upon but insulated from a supporting bar 160 carried by the base casting. Each spring contact 158 tends to engage 65 its associated contact finger 159 and also serves to hold a lug 161 on the horizontal arm of the corresponding bell crank lever 154 in engagement with the surface of a symmetrical cam 162, the latter forming a part of a cam sleeve 165 sleeved on a 70 horizontal shaft 133 and extending over the horizontal arms of the bell crank levers 154. The cam 162 is provided with a helical series of slots which, as the cam is rotated, successively pass over the lugs 161 of the bell crank levers 154. As the cor- 75

responding recess passes over one of the lugs, the associated switch contacts 158-159 are closed, provided the horizontal arm of the bell crank lever 154 is not restricted in its movement.

The shaft 163 is journaled in a side plate 164 and another rear side plate (not shown). On the sleeve 165 carrying cam 162 is a shoulder or cam 166, and the sleeve is splined to a driven portion 167 which constitutes a part of a positive clutch 10 through which power is communicated to the sleeve 165. The driven portion 167 of the clutch has integrally formed therewith a cam surface 168 which cooperates with an extending portion of a bail or clutch throwout lever 169 pivoted at 15 176, and functions as a disengaging means. A lateral projection of bail 169 cooperates with the armature of an electromagnet 170 which, when energized, withdraws the horizontal projection 177 of bail 169 free of the cam surface 168 and 20 its horizontal projection to allow member 167 to be shifted by spring 171 into cooperation with the driving portion 172 of the clutch which is secured to a shaft 163 on which is mounted a gear 173, the latter being meshed with a gear 94 and 25 driven continuously from power supplied by motor 88. Normally, of course, spring 171 tends to move driven portion 167 into cooperation with driving portion 172 of the positive clutch, but is prevented from such motion due to the cooperation 30 of the horizontally extending portion of bell crank lever 169 with the projection of cam surface 168. Consequently, the transmitting cam sleeve 165 which carries the cams 162 is normally held against rotation by the stop member or bell crank 35 lever 168, which is held in such position upon the de-energization of electromagnet 170.

As previously described, cooperating with each of the bell crank levers 154 is a bell crank lever 127, 128, 129, 131, and 132 which are positioned 40 in accordance with the position assumed by their respective sensing fingers 110. If the sensing finger 110 is held depressed, which will be the position it assumes if a perforation is not aligned therewith, the free end of its bell crank lever lies 45 in the path of the horizontal arm of its bell crank lever, such as 154. Thus, when the recess in cam 162 aligns with lug 161, the bell crank lever such as 154 is held against movement and the contacts 158-159 will be held open. However, if 50 a sensing finger 110 is allowed to ascend, which results from the presentation of a perforation in alignment therewith, its associated bell crank lever such as 154 is released upon the presentation of the recess of cam 162 thereto, which results 55 in the closure of contacts 158 and 159.

As sleeve 165 rotates, the recesses in cam 162 are presented successively to the lugs 161 on the bell crank levers 154 and the contacts 158 and 159 will be operated in a manner corresponding 60 to the position of the sensing fingers 110; that is, if the sensing fingers 110 sense a perforation in the tape 43, the associated bell crank levers 154 will be operated for effecting the sequential closure of contacts 158 and 159. However, if no 65 perforation is sensed, then the contacts 158 and 159 will not be allowed to close but will be held open in the position shown in Fig. 1.

Also secured to sleeve 165 are cams 174 and 175. Cam 174 cooperates with roller 139 secured to an 70 arm of bail 137 for operating the bail cyclically, as previously and to be subsequently described. Cam 175 cooperates with roller 151 secured to one arm of bell crank lever 149 and serves to operate stepping pawl 146 to engage the next succeeding tooth of ratchet wheel 144 and cause the 75

corresponding rotation of pin wheel 145 and, in turn, the relative movement of tape 43.

The periphery of shoulder 166 is formed as a cam having a recess to be entered by a roller 181 carried by a spring biased arm 182 pivoted to the 5 frame at 183. The purpose of the cam surface on shoulder 166, and particularly of the recess therein, in cooperation with roller 181, is to prevent singing or chattering of the clutch comprising driving portion 172 and driven portion 167 10 during periods of arrestment of the latter, and to control the initial rotation of cam 162. Since spring 171 opposes the disengagement of driven clutch portion 167 from driving portion 172, a slight torsional bias may be required to establish 15 and maintain a gap between the clutch portions after bare disengagement has occurred, it being understood that disengagement and separation of the clutch portions results solely from rotation of clutch throwout cam surface 168 against 20 stop member 169. Cooperation of roller 181 with the descending slope of the recess in the periphery of shoulder 166 provides the desired torsional bias.

Control of the initial rotation of cam 162 is 25 important because very early in a cycle of rotation it controls one of the bell cranks 154 to impress upon the telegraph line the start impulse, the effect of which is to set in operation any telegraph printer connected to the line. If cam 30 162 should be permitted to be rotated far enough to initiate the start impulse before firm engagement of the clutch portions is established, as, for example, by frictional engagement of the tips of the clutch teeth, distortion of some portion of the 35 signal combination to be transmitted is likely to result, due to subsequent slipping of the clutch portions into firm engagement and accompanying variation in the velocity of cam 162. The immediate establishment of firm engagement between the clutch portions may be assured by exerting upon the driven clutch portion 167 a drag sufficient to resist rotation due to frictional engagement between the teeth. The desired drag is furnished by engagement of roller 181 with the 40 periphery of shoulder 166 and particularly with the sharp ascending slope of the recess therein which roller 181 encounters substantially immediately upon the tripping of stop member 169.

Electromagnet 170 is controlled through contact springs 178 and 179 which are insulatedly mounted to a frame member. Contact spring 179 carries at its free end an insulator arranged to be engaged by an arm 180 formed on the member 141 of the frame 106. When the frames 105 and 106 are in the position shown in Fig. 1 45 with the plates 108 and 109 abutting plates 14 and 16 of the perforator, arm 180, as shown in Fig. 1, holds contact 179 free of contact 178. Instantly that frames 105 and 106 are moved 50 clockwise about their pivot, which occurs upon the operation of the perforator and the advancement of tape therefrom, arm 180 moves free of contact 179 and contacts 178 and 179 are thereupon closed to cause the energization of electromagnet 170. Electromagnet 170 is energized and 55 through its armature, withdraws stop latch 169 to allow spring 171 to move driven portion 167 rearwardly, as viewed in Fig. 3, or to the left as viewed in Fig. 4, to engage the driving portion 60 172 of the positive clutch. Sleeve 165 and the cams secured thereto are thereupon rotated.

Operation

For the purpose of clarity, let it be assumed 65

that all of the characters previously perforated in the tape 43 have been transmitted and that the sensing unit has been moved to a position where the plates 108 and 109 abut the plates 14 and 16 of the perforator. Under such circumstances, contacts 178 and 179 are opened and electromagnet 170 is de-energized, which results in stoppage of sleeve 165.

If, under such conditions, the keyboard perforator is operated through the depression of its key levers, the permutation bars 64-65 will be set permutable. For each depression of a key lever, mechanism is operated for rendering clutch 95 effective, whereupon power is communicated to sleeve 96, and in turn, to cam 97. The permuted setting of the permutation bars 64-65 causes a corresponding setting of interponents 18 through the actuation of levers 69 which, through the roller 71 by the action of spring 74, will be held in their set position. Certain of the interponents 18 will be positioned beneath and in alignment with the punches 13. Cam 97 now being rotated causes operation of lever 21 which, through adjustable sleeve 33, operates hammer 17 and through adjustable sleeve 37 and pin 38 operates punch 39 against the action of spring 41 to perforate a feed hole in tape 43. Operation of hammer 17 causes the movement of the punches 13 through the interponents 18 which have been positioned to the right, as viewed in Fig. 1, to perforate tape 43 with a transverse row of perforations symbolic of the character identified with the depressed key lever which caused the setting of the permutation bars 64 and 65. As hammer 17 was moved vertically, stepping pawl 49 was brought into engagement with the next succeeding tooth of ratchet portion 48. As cam 97 continues its rotation, spring 61 becomes effective to restore hammer 17 and stepping pawl 49 to their normal position of the position shown in Figs. 1 and 2. The downward movement of stepping pawl 49 causes pin drum 47 to rotate in a counterclockwise direction, as viewed in Fig. 2, and advance the tape 43 a distance determined by the distance between succeeding teeth on ratchet 48.

The advancement of tape 43 causes the movement of frame 106 about its pivot a distance equal to the distance through which the tape is advanced. Frame 105 remains in the position shown in Fig. 1, due to the action of springs 116 and 117, in which case the sensing fingers 110 are in alignment with the transverse row of perforations inserted in tape 43 as a result of the described depression of a key lever.

The movement of frame 106, as described, causes arm 180 to move free of contact 178, whereupon contacts 178 and 179 are closed and a circuit for the energization of electromagnet 170 is completed.

Electromagnet 170 withdraws, through its armature, latch 169 and frees the shoulder on the cam surface 168 of the driven portion 167 of the clutch which slides into engagement with the driven portion 172 of the clutch. However, until the driven and driving portions of the clutch are fully engaged, rotation of sleeve 165 is prevented, due to the cooperation of roller 181 on the periphery of shoulder 166. However, when the driven and driving portions of the clutch are fully engaged, sleeve 165 rotates.

As sleeve 165 rotates, cams 162, 174, and 175 rotate. Through cam 174, bail 137 is moved to allow, under the tension of their individual

springs 134, the movement of the sensing fingers 110 and the tape gripping rod 125. Sensing fingers 110 thus assume a position determined by the perforations in the tape. The tape 43, through rod 25, will be held against movement 5 relative to frame 105 during the period the sensing fingers 110 are sensing the perforations in tape 43 and the transmission of the impulses indicative of their setting.

Also, as sleeve 165 rotates, cam 162 identified 10 with the start impulse is effective on the bell crank lever 154 to cause the opening of contacts 158 and 159 for the transmission of a start impulse. Significant, of course, is the fact that for each cycle of rotation of sleeve 165, the bell 15 crank lever 154 identified with the start impulse will be actuated invariably to cause the opening of its contacts 158 and 159 to transmit the starting impulse. As sleeve 165 continues its rotation, its cams 162 are presented sequentially to 20 lugs 161 on the bell crank levers 154 which, as previously described, are released to close contacts 158 and 159, if a sensing finger 110 finds a perforation in the tape 43. If the sensing finger 110 fails to find a perforation in tape 43, then bell crank lever 154, through the bell crank lever individual to that particular sensing finger, will be restrained against movement and will not close contacts 158 and 159. Through the rotation of sleeve 165, the impulses identified with the particular transverse row of perforations will be transmitted.

During the transmission of the impulses through the operation of contacts 158 and 159, cam 175 is effective for causing the operation of stepping pawl 146. Stepping pawl 146 is moved positively upwardly by cam 175 to engage the next succeeding tooth on the ratchet wheel 144 when it is moved downwardly by a spring 184 to rotate pin wheel 145. However, at that instant, rod 125 has been moved upwardly and engaged tape 43 to hold it against movement. Under such a condition, the tape 43 being held against movement, frame 106 will be rotated in a clockwise direction about its pivot, as viewed in Fig. 1, to approach frame 105.

After the last of the several bell crank levers 154 has been subjected to the action of the last of the cams 162, cam 174 operates bail 137 to rotate bell crank levers 121-132 in a clockwise direction, as viewed in Fig. 1, to withdraw the sensing fingers 110 and the tape gripping rod 125.

If, during the cycle of rotation of shaft 163 just described there has been no further operation of the key levers 62, the frame 105 remains in abutting relation with the plates 14 and 16. However, if, during the cycle of rotation of shaft 163 another key lever 62 or other key levers 62 have been depressed, tape 43 will be advanced through the operation of pin drum 47, in which case the tape will be pulled by the action of pin wheel 145 through the frame 105 and the transverse rows of perforations in the tape 43 will be sensed successively and the impulses indicative thereof will be transmitted upon the rotation of sleeve 165.

If the keyboard perforator is operated at a speed considerably faster than the speed of operation of sleeve 165, the frames 105 and 106 will be rotated to the position shown in Fig. 2 70 when a loop of tape, as shown in Fig. 3, will form between the frame 105 and the plates 14 and 16 of the perforator. As the pin wheel 145 rotates, the tape 43 will be presented to the tape sensing fingers 110.

If there is a prolonged cessation in the operation of the perforator, the loop of tape shown in Fig. 2 will be consumed and the tape between the frame 105 and the exit channel of the perforator will become taut, as indicated by the dotted lines in Fig. 2. Under such conditions, the frames 105 and 106 will be advanced in clockwise direction about their pivot along the tape 43. During such movement, the successive 10 rows of perforations will be sensed and the impulses indicative thereof will be transmitted through the rotation of sleeve 165.

If, during the aforementioned movement of frames 105 and 106 in clockwise direction there is no operation of the perforator, the movement of the frames 105 and 106 continues until frame 105 abuts the plates 14 and 16 of the perforator. When in such position, the last row of perforations in tape 43 will be sensed and the impulses identified therewith will be transmitted. Also, arm 188 will have engaged contact 178 to open contacts 178 and 179 to deenergize electromagnet 170. Electromagnet 170, upon being deenergized, restores the stop latch in the path of cam surface 168 which, upon being engaged, forces driven portion 167 against the tension of spring 171 to the right, as viewed in Fig. 4, whereupon a disengagement between the driven and driving portions of the clutch occurs and sleeve 165 is thus stopped.

Upon a resumption in the operation of the perforator, contacts 178 and 179 are closed and electromagnet 170 is energized, with the result that sleeve 165 rotates for continuing the operation as previously described.

While the invention has been disclosed and described with reference to a particular type of apparatus, it is obvious that it may be applied to other forms of apparatus without departing from the spirit and scope of the present invention.

What is claimed is:

1. In combination with a perforator for applying code perforations and feed perforations in a strip, a unit including two frames, sensing fingers in one of said frames for sensing code perforations, feed mechanism in the other frame cooperating with the feed perforations for advancing the strip, a pivoted lever secured to each of said fingers and responsive to their position, a plurality of electrical contacts, and a rotary distributor operative upon the movement of one of said frames to operate said contacts in accordance with the position of said levers.

2. In combination with a perforator for applying code perforations and feed perforations in a strip, a unit including two frames, sensing fingers in one of said frames for sensing code perforations, feed mechanism in the other frame cooperating with the feed perforations for advancing the strip, a pivoted lever secured to each of said fingers and responsive to their position, a plurality of electrical contacts, and a rotary distributor including means to operate said feed mechanism and to actuate said contacts in accordance with the position of said levers.

3. In combination with a perforator for applying code perforations and feed perforations in a strip, a unit including two pivoted frames, sensing fingers in one of said frames for sensing code perforations, feed mechanism in the other frame cooperating with the feed operations for advancing the strip, a pivoted lever secured to each of said fingers and responsive to their position, a plurality of electrical contacts, and a rotary

distributor operative when one of said frames is rotated on its pivot including means to operate said feed mechanism and to actuate said contacts in accordance with the position of said levers.

4. In combination with a perforator for applying code perforations and feed perforations in a strip, a unit including two frames, sensing fingers in one of said frames for sensing code perforations, feed mechanism in the other frame 10 cooperating with the feed perforations for advancing the strip, a pivoted lever secured to each of said fingers and responsive to their position, a plurality of electrical contacts, a rotary distributor, and means responsive to one of said 15 frames for releasing said distributor to operate said contacts in accordance with the position of said levers.

5. In combination with a perforator for applying code perforations and feed perforations in 20 a strip, a unit including two frames, spring means interconnecting said frames to allow their individual movement, sensing fingers in one of said frames for sensing the code perforations, feed mechanism in the other of said frames cooperating 25 with the feed perforations for feeding the strip past said sensing fingers, signal transmitting means, means for operating said transmitting means in accordance with the setting of said fingers, means for operating said feed mechanism, and means effective during the operation of said feed mechanism for holding said strip 30 against movement.

6. In combination with apparatus for applying an unlimited number of permanent indicia on a 25 record strip, a sensing unit including a pair of pivoted frames, means for normally maintaining said frames in a predetermined relationship with each other, sensing elements carried by one of said frames, strip advancing mechanism carried 30 by the other of said frames, means responsive to the control of said elements as determined by the indicia on said strip, a plurality of contacts, means for operating said contacts sequentially 35 in accordance with the operation of said means through said sensing elements, and means for operating said strip advancing mechanism to advance the strip to bring successive indicia in alignment with said sensing elements and for advancing said sensing elements along said strip 40 to a point immediately adjacent the point of 45 application of said indicia when a predetermined condition prevails in said strip.

7. In combination with a perforator for applying code perforations and feed perforations 50 in a strip, a unit including two pivoted frames, spring means interconnecting said frames, sensing fingers in one of said frames for sensing the code perforations, tape holding means in the frame with said sensing fingers, feeding mechanism in the other frame cooperating with the feed perforations for advancing the strip, means secured to each of said fingers and responsive to their position, a plurality of electrical contacts, a rotary distributor operated upon the movement of one of said frames to operate said contacts in accordance with the position of said levers, and means for operating said tape feeding mechanism and said tape holding mechanism whereby one of said frames is moved about 55 its pivot against the action of said spring means.

8. A telegraph transmitter including two frames, a sensing element in one of said frames for sensing signal indicia in a strip, mechanism in the other frame for advancing said strip to present the indicia to said sensing element,

- means controlled by said sensing element, and means to operate said mechanism for each group of signal indicia in said strip and to distribute signal impulses in accordance with the 6 response of said means to said element.
9. A telegraph transmitter including two frames, sensing fingers in one of said frames for sensing code indicia in a strip, feed mechanism in the other frame cooperating with feed perforations in said strip for advancing the 5 strip, a pivoted lever secured to each of said fingers and responsive to their position, electrical contacts, and a rotary distributor including means to operate said feed mechanism and to actuate said contacts in accordance with the 10 position of said levers for transmitting signal impulses in accordance with the indicia in the strip.
10. A telegraph transmitter including two frames, sensing fingers in one of said frames for sensing code perforations in a strip, feed mechanism in the other frame cooperating with feed perforations in said strip for advancing the 5 strip, a pivoted lever secured to each of said fingers and responsive to their position, electrical contacts, and a rotary distributor including means to operate said feed mechanism and to actuate said contacts in accordance with the 10 position of said levers for transmitting signal impulses in accordance with the indicia in the strip.
11. A telegraph transmitter including two frames, sensing fingers in one of said frames for sensing code indicia in a strip, feed mechanism in the other frame cooperating with feed perforations in said strip for advancing the 5 strip, a pivoted lever secured to each of said fingers and responsive to their position, electrical contacts, and a rotary distributor including means to operate said feed mechanism and to actuate said contacts in accordance with the 10 position of said levers for transmitting signal impulses in accordance with the indicia in the strip.
12. A telegraph transmitter including two frames, sensing fingers in one of said frames for sensing code indicia in a strip, feed mechanism in the other frame cooperating with feed perforations in said strip for advancing the 5 strip, a pivoted lever secured to each of said fingers and responsive to their position, electrical contacts, and a rotary distributor including means to operate said feed mechanism and to actuate said contacts in accordance with the 10 position of said levers for transmitting signal impulses in accordance with the indicia in the strip.
13. A telegraph transmitter including two frames, sensing fingers in one of said frames for sensing code indicia in a strip, feed mechanism in the other frame cooperating with feed perforations in said strip for advancing the 5 strip, a pivoted lever secured to each of said fingers and responsive to their position, electrical contacts, and a rotary distributor including means to operate said feed mechanism and to actuate said contacts in accordance with the 10 position of said levers for transmitting signal impulses in accordance with the indicia in the strip.
14. A telegraph transmitter including two frames, sensing fingers in one of said frames for sensing code indicia in a strip, feed mechanism in the other frame cooperating with feed perforations in said strip for advancing the 5 strip, a pivoted lever secured to each of said fingers and responsive to their position, electrical contacts, and a rotary distributor including means to operate said feed mechanism and to actuate said contacts in accordance with the 10 position of said levers for transmitting signal impulses in accordance with the indicia in the strip.
15. A telegraph transmitter including two frames, sensing fingers in one of said frames for sensing code indicia in a strip, feed mechanism in the other frame cooperating with feed perforations in said strip for advancing the 5 strip, a pivoted lever secured to each of said fingers and responsive to their position, electrical contacts, and a rotary distributor including means to operate said feed mechanism and to actuate said contacts in accordance with the 10 position of said levers for transmitting signal impulses in accordance with the indicia in the strip.
